(57) **CLAIM**

The ornamental design for a ring holder attachable to phone tether tab, as shown and described.

DESCRIPTION

1. Ring holder attachable to phone tether tab

1.1 : Perspective

1.2 : Front

1.3 : Back

1.4 : Top

1.5 : Bottom

1.6 : Left

1.7 : Right

1.8 : Reference

The parts shown by means of broken lines in the reproductions are not part of the claimed design; the parallel thin lines and the radial thin lines in the representation represent contours only and do not illustrate an ornamentation or decoration on the surface of the product.
